James Scarr Attorney

UNITED STATES PATENT OFFICE.

JAMES SCARR, OF RANDSBURG, CALIFORNIA.

CLEANER FOR KITCHEN UTENSILS.

1,210,850.

Specification of Letters Patent. Patented Jan. 2, 1917.

Application filed June 5, 1915. Serial No. 32,406.

To all whom it may concern:

Be it known that I, JAMES SCARR, a subject of the King of Great Britain, residing at Randsburg, in the county of Kern and 5 State of California, have invented certain new and useful Improvements in Cleaners for Kitchen Utensils, of which the following is a specification.

This invention relates to implements employed for scraping pans, kettles and like utensils, and which may likewise be employed for cleaning sinks and the like, and has for one of its objects to improve the construction and increase the efficiency and utility of devices of this character.

Another object of the invention is to provide a simply constructed device which may be inexpensively manufactured and of any required size.

With these and other objects in view, the invention consists in certain novel features of construction as hereinafter shown and described, and then specifically pointed out in the claims; and in the drawings illustrative of the preferred embodiment of the invention—

Figure 1 is a perspective view of the improved implement from beneath; Fig. 2 is a transverse section on the line 2—2 of Fig. 30 1; Fig. 3 is a side elevation. Fig. 4 is a view of the blank from which the body portion of the improved device is constructed.

The improved device comprises a body portion 10 having a laterally directed flange 35 or rim along one side, as represented at 11, across one end as represented at 12, and partially along the other side as represented at 13, the flanges 11 and 12 being preferably rounded where united, as shown, to facilitate the operation. The parts 10—11—12 are preferably pressed from a single sheet 40 of relatively thin metal, preferably steel, and with the edges of the flange portion 11—12—13 sharpened or knife-edged, as shown. A handle 14 is connected to the body 10, preferably by rivets, as shown at 45 15 and at an incline to the longitudinal plane of the body.

The body 10 may be of any required size, 50 and the flanges of any required width, the body 10, together with its flanges, being as light as possible consistent with the strains to which it will be subjected.

A convenient and useful implement is thus

produced which may be cheaply manufactured and which will be found very useful for scraping pans, kettles and like utensils to remove adhering particles of grease and other matter, and which may likewise be employed for cleansing sinks and like structures.

The longer laterally extending portion 11, when placed flat upon the surface to be cleaned, is in position to receive any previously loosened material when brushed thereon, and the matter thus received is readily removed over the unflanged portion of the body.

Having thus described the invention, what is claimed as new is:—

1. As a new article of manufacture, a scraper for cooking utensils comprising an elongated body portion open at its rear end and provided at its front end and side edges with upstanding flanges, each terminating in a knife edge, one of the side flanges being longer than the other and both of said side flanges extending in the direction of the open end of said body portion, and a handle secured to the lower surface of the body portion at the open end thereof with its free end disposed at an angle to said surface.

2. As a new article of manufacture, a scraper for cooking utensils comprising an elongated body portion open at its rear end and having smooth upper and lower surfaces, there being a flange projecting laterally from the upper surface of the body portion at the front end thereof and side flanges projecting from said upper surface and formed integral with the front flange, one of said side flanges being shorter than the other and all of said flanges terminating in knife edges, the corner of the body portion at the junction of the long side flange and front flange being rounded, and a handle extending longitudinally from the open end of the body portion and having its free end disposed at an angle to the lower surface thereof.

3. As a new article of manufacture, a scraper for cooking utensils comprising an elongated body portion having its rear end open and curved transversely and its upper surface smooth and unobstructed, said body portion being provided at its front end with an upstanding flange and at its side edges with upstanding flanges of different lengths

and extending in the direction of the open end of the body portion, the corner of the body portion at the junction of the short flange and front flange being angular and 5 the corner of the body portion at the junction of the long flange and front flange being curved, and an operating handle extending longitudinally from the open end of the

body portion with its free end disposed at an angle thereto.

In testimony whereof I affix my signature in presence of two witnesses.

JAMES SCARR. [L. S.]

Witnesses:

JAMES MONTGOMERY,

JOSEPHINE MONTGOMERY.
